BED AND THE LIKE

Thomas M. Butler, Chicago, Ill.

Application May 4, 1934, Serial No. 723,873

4 Claims. (Cl. 5—329)

This invention relates to improvements in beds and has for a particular object the provision of means for dividing off a bed into two portions, separating one portion from another. It is well-known that many sleepers are restless and cause much annoyance to others, resulting in loss of sleep and health, as will be particularly manifest in the case of sick persons. To eliminate such disadvantages and others which will be manifest, I have devised means which in the form shown to illustrate the principle of my invention takes the form of a board partition which runs lengthwise of the bed and centrally thereof to divide the bed into two equal portions.

15 The invention will be best understood by reference to the accompanying drawing of some concrete exemplifications chosen to apply the principle of the invention, and in which:

Fig. 1 is an elevational view partly in section 20 taken from the side of a bed showing one form which my invention might take as applied to a bed;

Fig. 2 is a plan view of a form of partition element hereinafter referred to; and

25 Fig. 3 illustrates a strap and ring used for strapping the ring to a bedpost or support for a purpose hereinafter more fully described.

The form of construction illustrated in Fig. 1 is applied to a bed which in the embodiment shown 30 in Fig. 1 has a tubular type foot end support 10 and a tubular type head end support 11, and the foot end support 10 is provided with upper tubular cross member 12 and lower tubular cross member 13. The head end support 11 is similarly 35 provided with upper tubular cross member 14 and lower tubular cross member 15. The end supports 10 and 11 are linked together by means of a pair of tie rods, one of them, 16, being shown in Fig. 1. The tie rods may support the usual spring 40 17, mattress 18, and covering 19. A plurality of straps 20, to wit, four in number, in the form shown, are provided, one for each of the aforementioned four cross members. Each of these straps is provided with a buckle 21 and each strap 45 has affixed thereto in an obvious manner or may carry loosely a ring 22. One strap 20 for example is adapted to be linked about the upper tubular cross member 12 centrally thereof in such a manner that the ring 22 is adapted to be positioned 50 on the side of the foot end support 10 which faces the opposite head end support 11. In the same way another of the straps 20 is linked about the lower tubular cross member 13 centrally thereof with the ring thereof positioned in a manner 55 substantially beneath the ring of the strap on the

upper tubular cross member 12. The upper tubular cross member 12 and the lower tubular cross member 13 of the head end support 11 are each provided with straps 20 and rings 22 in a substantially similar manner with the rings thereof positioned on the side of the head end support 11 which faces the opposite foot end support.

Thus far has been described the means to lock the same with the preferred form of bed partition of my invention. Referring to the bed partition itself as shown in Fig. 1, this partition 23 includes a rectangular board 24 which may be made of wood or other material, which board may be of any length but is preferably made shorter than at least the normal bed so that it may be adapted to beds of different sizes. The board 24 is provided with a pair of cleats 25 by any common fastening means on one side thereof in the preferred form which has been chosen to illustrate the principle of the invention, and these cleats 20 are of sufficient dimensions to receive a plurality of eye-bolts 26 having eyes 27 and adapted to be locked by nuts 28 as will be apparent from Figs. 1 and 2. It will be seen from Fig. 1 that in the form shown, each of these cleats is provided with three 25 of the eye-bolts with eyes and nuts with the eyes 27 of each three registering with each other, whereby a rod may be passed through the eyes of either group of three bolts. It will also be seen particularly from Fig. 2 that the eye of any cleat 30 may be manipulated outwardly from the cleat or inwardly toward the cleat.

The structure of the form shown, excepting for the locking means, has been described and in the operation of the device the partition 23 is rested 35 endwise and lengthwise upon the covering 19 so as to divide the covering and bed into two equal portions with the plane of the partition bisecting the planes of the foot end support and the head end support, 10 and 11 respectively. In this 40 condition the eyes of one group of eye-bolts registering with each other as aforesaid should also register with the link 22 supported from the upper cross member 12 and the link 22 supported on the lower cross member 13 of the foot end 45 support, between which links said group of three eyes is located. As shown in Fig. 1 a locking rod 29 is adapted to be inserted through the said links 22 and the eyes 27. The locking rod may be maintained in position by a head 30 abutting with 50 the link 22 of the upper cross member 12. In the same way three eyes of the group of eye-bolts at the opposite end of the partition 23 are made to register with the links 22 of the upper and lower cross members of the head end support 11 and 55

in the same way another rod 29 is inserted through the registering links and eyes to lock the same and is retained in position by means of head 30.

5 As hereinbefore stated the type of bed to which my invention is applied in the form shown in Fig. 1 is of the familiar tubular bedstead type.

It will be manifest from the foregoing that I have provided partitioning means and effective 10 means for locking said means in position and means for adjusting the partitioning means to fit beds of different sizes. If it is desired to use a partition of a particular size with a larger bed all that is necessary is to manipulate the eye- 15 bolts in the nuts outwardly from the cleats and partition and vice versa.

While I have shown concrete exemplifications 20 of the application of the principle of my invention these forms do not circumscribe my invention but my invention is capable of being exemplified in a large variety of forms.

It will be apparent that by my invention means 25 easy of handling have been provided to accomplish the objects set forth. In addition, by the means I have provided as will be apparent it will be a simple matter to remove the covering and the like. It will also be apparent that my invention is capable of application to any bed and that the means provided are not only simple in 30 operation and manufacture, but are inexpensive, besides being capable of ready application by any one.

My invention is not limited to the exemplifications selected for the purpose of illustration, and 35 these may be changed in numberless respects without departing from the spirit of the invention. I therefore do not wish to be limited to the precise details of construction set forth but desire to avail myself of all such variations and 40 modifications as come within the scope of the appended claims.

Having thus described my invention, what I 45 claim as new and desire to secure by Letters Patent is:

1. In a device of the kind described a bed frame having a foot end support and head end support and tie rod means connecting said supports, a par-

tion for dividing said bed into two portions, said partition being provided with cleats, each cleat being provided with a plurality of adjustable eye-bolts, straps adapted to be supported by said end supports, and rings adapted to be supported by 5 said straps, and locking rods adapted to be inserted in the rings and eye-bolts at each end of the bed to lock the partition in place.

2. In a device of the kind described a bed frame 10 having a foot end support and head end support and tie rod means connecting said supports, a partition for dividing said bed into two portions, a plurality of eye-bolt members threadedly secured to the ends of said partition, straps adapted 15 to embrace and be supported by said end supports, rings supported by said straps, and locking rods adapted to be inserted in the rings and eye-bolts at each end of the bed to lock the partition in place.

3. In a device of the kind described a bed frame 20 having a foot end support and head end support and tie rod means connecting said supports, a partition for dividing said bed into portions, a plurality of eye-bolt members threadedly secured to the ends of said partition, straps adapted to 25 embrace and be supported by said end supports, rings supported by said straps, locking rods adapted to be inserted in the rings and eye-bolts at each 30 end of the bed to lock the partition in place, said partition being of less length than the normal distance between said end supports, and said eye-bolt members being extensibly secured to said partition.

4. In a device of the kind described a bed frame 35 having a foot end support and head end support and tie rod means connecting said supports, a partition for dividing said bed into two portions, a plurality of eye-bolt members threadedly secured to the ends of said partition, straps adapted 40 to embrace and be supported by said end supports, rings supported by said straps, and locking rods adapted to be inserted in the rings and eye-bolts at each end of the bed to lock the partition in place, each of said locking rods having 45 an enlarged head for support by a pair of said rings.

THOMAS M. BUTLER.
